UNITED STATES PATENT OFFICE

138,962

DESIGN FOR A CAMERA CASE

Arthur Ringer, Paola, Kans.

Application June 29, 1944, Serial No. 114,257

Term of patent 7 years

(Cl. D61—1)

To all whom it may concern:

Be it known that I, Arthur Ringer, a citizen of the United States and a resident of Paola, Miami County, Kansas, have invented a new, original, and ornamental Design for Camera Cases, of which the following is a specification, reference being had to the accompanying drawing, forming part thereof.

In the drawing:

I claim:

The ornamental design for a camera case, substantially as shown and described.

ARTHUR RINGER.
